CONTAINER WITH SPOUT AND CAP THEREFOR HAVING MEANS ON SAID SPOUT TO PUNCTURE SAID CAP

Walter E. Horrocks, Lakewood, Ohio

Application December 2, 1952, Serial No. 323,610

17 Claims. (Cl. 222—83)

1

My present invention relates to containers provided with puncturing means sealed within the container structure and arranged to puncture and bend the bottom of the primary sealing means outwardly.

An important object is to provide the container with auxiliary sealing means.

Another important object is to provide the container with auxiliary sealing means arranged to prevent mixing with the released contents of the container.

Another object is to provide the container with auxiliary seals having compressible characteristics.

Another object is to provide the containers with auxiliary seals having distortable characteristics.

Another object is to provide the container with a primary sealing cap adapted to confine and support the auxiliary sealing means around its spout.

A still further object is to provide the container with triple seals.

Other objects and advantages of the invention will be apparent during the course of the following description.

In the accompanying drawing forming a part of this specification, and in which like numerals are employed to designate like parts throughout the same.

Fig. 1 illustrates a sectional view of a completely assembled container structure embodying the features of the present invention and showing a third seal at X.

Fig. 2 is an enlarged sectional view showing the preferred type of primary sealing cap.

Fig. 3 is an enlarged sectional view of the outlet spout shown in Fig. 1.

Fig. 4 is a sectional view of a container structure provided with an extension spout telescoped over the sealing cap and showing the bottom of the primary sealing cap after it has been punctured and bent outwardly.

Fig. 5 illustrates a sectional view of an assembly with the container embodying a modified outlet spout supporting the auxiliary seal with the assembly being supported on a tubular funneling element receiving the released contents.

Fig. 6 is a fragmentary sectional view of the spout employed in Fig. 5 provided with a cork auxiliary seal and.

Fig. 7 is a fragmentary sectional view of a spout provided with a rubber auxiliary seal.

In the accompanying drawing which illustrates examples of the invention without de-

2

fining its limits, Fig. 1 shows a container holding structure C provided with an outlet aperture 10 which coincides with the inner side of a tubular spout portion 11 which is attached to the container structure C. The tubular spout portion 11 is preferably cut at an acute angle as shown at 12 and is provided with a puncturing edge preferably as shown at 13. The spout portion 11 of the container C is primary sealed on the end with a cap portion preferably of the type shown in Fig. 2 in which its tubular wall surrounds the tubular wall of the spout portion 11 with the bottom of the primary sealing cap in close proximity or in contact with the puncturing edge 13 and the outwardly projecting flange 14 providing a means to rest on the top end of a tubular receiving element 15 as shown in Fig. 5. The spout portion 11 is provided with a groove or recess 16 which provides a reduced tubular section around the spout 11 to receive and retain an auxiliary seal 17 substantially as shown, and the primary sealing cap portion is initially maintained about the spout 11 with a hermetical seal such as sealing wax or its equivalent as indicated at X which is susceptible to be sheared by axial movement of the cap on the spout.

Fig. 2 shows a preferred primary sealing cap provided with a rounded corner 18 at the flanged end providing a means to initially engage the protruding end 19 of the auxiliary seal 17 which is shown in Fig. 3 in which the dotted lines D indicate the line of travel such as when the spout portion 11 is to enter into the primary cap portion shown in Fig. 2 so that the protruding end 19 of the auxiliary seal 17 initially engages the rounded corner 18 and as the primary cap is forced over the spout 11 the auxiliary seal 17 is compressed between the wall of the spout portion 11 and the wall of the primary sealing cap substantially as shown in Fig. 1 and Fig. 4 respectively.

Fig. 3 shows the auxiliary seal 17 seated in a groove 16 provided around the spout portion 11 before the primary cap is placed over the spout 11 in which the tapered sides 20 of the auxiliary seal 17 provide a means for initially entering into the primary sealing cap shown in Fig. 2 and then being further compressed, or distorted, as the case may be by the tubular wall of the primary sealing cap against the tubular wall of the spout portion 11 substantially as shown in Fig. 1 and Fig. 4.

Fig. 4 is a sectional view of a container structure C provided with an outlet aperture 10 which surrounds a tubular spout portion 11 which is

attached to the structure C, and the primary cap is further provided with an attached extended spout portion 21 which arrangement provides the primary cap with a bottom axially disposed below the open end of the spout portion 21 in the position as indicated at 22, with the bottom 22 being shown bent outwardly such as after an axial pressure has been applied to the end of the extended spout 21. It is to be noted that the bottom of the projecting flange 14 of 10 the primary sealing cap is arranged to contact the top side of the container C in such a manner to allow of the short side of the spout portion 11 to bend the punctured bottom of the primary sealing cap outwardly and at the same 15 time confine the auxiliary seal 17 between the tubular wall of the primary sealing cap and the tubular wall of the spout 11 in such a manner that the auxiliary seal 17 can not be dislodged and become mixed with the contents discharging 20 from the container C.

Fig. 5 illustrates a preferred version of the invention in a sectional view showing the container structure C provided with an outlet aperture 10 which surrounds a tubular spout portion 11 which is attached to the container C and being provided with a reduced end 23 and having its primary sealing cap positioned on the end of a tubular receiving element 15 such as is standard automobile equipment for introducing oil into the crank case of automobile engines in which the bottom of the primary sealing cap has been punctured and bent downward by the reduced end 23 of the tubular spout 11 in which the auxiliary seal 17 surrounding the reduced end 23 of 35 the tubular spout 11 is confined on the ledge 24 of the primary sealing cap, which ledge is provided as when the reduced end 23 of the tubular spout punctures an aperture that is substantially smaller in diameter than the inside diameter of the tubular walls of the primary sealing cap and thereby confining the auxiliary seal on the ledge 24 as is thus provided in the primary sealing cap in such manner that it can not become dislodged and become mixed with the contents discharging from the container C after the bottom of the primary sealing cap has been punctured and bent outwardly as shown substantially in Fig. 5.

Fig. 6 shows a fragmentary sectional view of the spout 11 shown in Fig. 5 before the spout is inserted into the primary cap with the auxiliary sealing means 17 surrounding the reduced tubular wall 23 of the spout 11 and having the outer side 20 of the sealing means 17 tapered which allows of the rounded corner 18 of the primary sealing cap shown in Fig. 2 to easily initially engage the small end of the auxiliary seal 17 and then further gradually compress it, or distort it, as the case may be, around the tubular wall of the spout 11 and against the tubular wall of the primary sealing cap substantially as shown in Fig. 5, such as when the bottom of the primary sealing cap has been punctured by applied axial pressure on the container to allow of the container's contents to be discharged into the tubular receiving element 15.

Fig. 7 shows a fragmentary sectional view of a tubular spout 11 such as is shown in Fig. 1, Fig. 3, and Fig. 4 having a recess or groove 16 provided around the tubular wall providing a reduced wall section for utilizing an auxiliary seal 17a which will allow of the rubber ring to distort into the recess or groove and press against the inner side of the tubular sealing cap wall and 70 75

against the tubular wall of the spout 11 to provide means for holding an auxiliary sealing means substantially as illustrated in Fig. 1 and Fig. 4 respectively. It is to be noted that the seals 17 and 17a can be made of either cork or rubber elements or their equivalents and the spout 11 can be provided with both the recess shown in Fig. 4 and the reduced end shown in Fig. 5, if it is so desired.

It is to be further noted that in addition to holding substances within the container with the primary sealing cap the auxiliary sealing means incorporated and described herein provides an additional sealing means to prevent the seepage of penetrating substances for which the primary sealing cap may be inadequate, and the hermetically sealing means disclosed herewith at X in Fig. 1 provides a means to triple seal the container against allowing of the seepage of penetrating contents from the container and also to maintain the primary sealing cap in a temporary fixed position on the spout 11 until such a time that the seals are to be broken to allow of the contents within the container to be discharged therefrom. When axial pressure is applied on the bottom of the container structure, or on the end of the extended spout as the case may be, the puncturing means provided on the spout 11 will puncture an aperture through the bottom of the primary sealing cap and also at the same time break the hermetical seal around the spout 11 as shown at X in Fig. 1, which thereby with one operation, allows of the triple sealing means to instantly release the contents within the container to flow outwardly through the spout 11 or 21 as the case may be, or flow into the tubular receiving element 15 as is shown in the assemblage in Fig. 5, and which receiving element 15 is applicable for use with either of the Figures 1, 4, and 5.

It is to be understood that the form of my invention, herein shown and described, is to be taken as preferred examples of the same, and that various changes in the shape, size and arrangement of parts may be resorted to, without departing from the spirit of my invention, or the scope of the subjoined claims, and I reserve the right to the use of various elements, or combination of elements, for constructing the containers and seals without departing from the scope of the appended claims.

This application is an improvement over the subject matter disclosed in my copending application Serial No. 198,861, filed December 1, 1950 for Container, as the present container may be used in the same manner as is described therein with the additional auxiliary sealing means described in this application being incorporated in order to provide a more effective sealed container, and also to disclose that the flanged end of the primary sealing cap may be hermetically sealed around the tubular spout 11 and the primary sealing cap as is indicated at X in Fig. 1. It is also intended that the containers are to be used without the third seal X, if it is so desired.

Having described my invention, what I claim and desire to secure by Letters Patent is as follows in the accompanying claims in which I claim:

1. A container of the character described comprising, in combination, a holding structure having outlet means, a tubular outlet spout connected to the container about the outlet means, said spout having a reduced tubular section therewith, puncturing means on the end of the spout,

a primary sealing means providing a cap fitted around the spout above and below the puncturing means, and an auxiliary sealing element arranged around the reduced tubular section of the said spout between the walls of said cap and said spout.

2. A container as described in claim 1 including a third sealing means around the said spout initially holding the primary sealing means to the said spout.

3. A container of the character described comprising a container structure having outlet means, a tubular outlet spout attached to the container about the outlet means, puncturing means on the end of the spout, a primary sealing means providing a cap fitted around the spout above and below the puncturing means, a groove provided around the spout, and an auxiliary sealing means arranged in the groove about the spout between the walls of the primary sealing means and the said spout.

4. A container as described in claim 3 including a third sealing means around the said spout initially holding the primary sealing means to the said spout.

5. A container of the character described comprising a container having outlet means, a tubular outlet spout attached to the container about the outlet means, puncturing means on the end of the spout, a primary sealing cap fitted around the spout above and below the puncturing means, a portion of the wall of the said spout having a reduced tubular wall section therearound, and an auxiliary seal arranged around the reduced tubular wall section of the said spout between the wall of said cap and said spout.

6. A container as described in claim 5 including a third sealing means around the said spout initially holding the primary sealing means to the said spout.

7. The assemblage as described in claim 1 including a tubular receiving element arranged to support the said assemblage and funnel the contents from the said container.

8. The assemblage as described in claim 5 including a tubular receiving element arranged to support the said assemblage and funnel the contents from the said container.

9. A container comprising a holding structure having outlet means, a tubular outlet spout attached to the said structure about the outlet means, puncturing means on the end of the said spout, said spout further provided with a reduced tubular section therearound, a slideable primary sealing cap having a cylindrical wall, a bottom, and an outwardly projecting flange including a rounded shoulder merging the said flange with the said wall, fitted on the said spout around and over the puncturing means, and an auxiliary seal arranged around the reduced tubular section of the said spout between the said section of the said spout and the said wall of said cap.

10. A container as described in claim 9 including a third sealing means arranged around the said spout initially holding the primary sealing means to the said spout.

11. The assemblage as described in claim 9 including a tubular receiving element arranged to support the said assemblage and funnel the contents from the said container.

12. A container of the character described com-

prising a container structure having outlet means, a tubular outlet spout coinciding with the outlet means and attached to the said container including a reduced tubular section extending to the bottom of the said spout, puncturing means on the end of the said spout, a primary sealing means providing a slideable cap fitted around the said spout above and below the said puncturing means, and an auxiliary sealing means arranged between the wall of the said reduced tubular section and the wall of the primary sealing means.

13. A container as described in claim 12 including a third sealing means around the said spout initially holding the primary sealing means to the said spout.

14. The assemblage as described in claim 12 including a tubular receiving element arranged to support the said assemblage and funnel the contents from the said container.

15. In a container of the character described having a tubular puncturing outlet spout including a reduced tubular section therearound, and a primary sealing cap covering the end of the outlet spout with an auxiliary sealing means arranged around the said reduced section of the spout and a hermetical sealing means arranged around the said spout initially sealing the said cap to the said spout in such a manner that all of said seals may be broken simultaneously when axial pressure is applied to the bottoms of said containers, substantially as described.

16. A container of the character described comprising a container structure having outlet means, a tubular outlet spout attached to the container about the outlet means, said spout provided with a reduced tubular section extending to the bottom end of the spout, puncturing means on the end of the reduced section, and a slideable sealing means providing a cap fitted around the spout above the reduced section and extending around and across the puncturing means of the reduced section.

17. In a container of the character described, as a subcombination, an outlet spout providing a solid tubular wall free from serrated ends with the top end of the spout having a free open end adapted to coincide with the perimeter of an outlet aperture, and the opposite pouring end of the said spout providing a reduced tubular wall section including puncturing means arranged about the pouring end of said spout.
